WING ASSEMBLY FOR ROAD GRADERS

Paul W. Grabow, Twin Brooks, S. Dak.

Filed Apr. 16, 1958, Ser. No. 728,929

1 Claim. (Cl. 37—155)

This invention relates to earth moving equipment and more particularly to a wing assembly for road graders.

An object of the invention is to provide a smoothly operative and conveniently used wing assembly for a road grader, the wing assembly being capable of adjustment by the operator of the grader without leaving his seat.

There have been prior adjusting devices for moldboards and other earth moving attachments or equipment. This invention differs from any others by being of exceedingly simple construction but yet capable of performing the necessary adjusting operation with ease and facility.

The invention centers largely about a novel structural organization including a support beam that has a guiding rib along one edge, the rib passing through a guide sleeve and adapted to be locked to that guide sleeve which is carried by a part of the road grader. The locking is achieved by a locking pin operated by a pull rope, cable, etc. whose end is at the seat of the grader. The locking pin can be manipulated against the opposing yielding bias of the spring and withdrawn from one of the many openings in the centering rib. Then the force generated by movement of the grader and the soil, gravel, etc. that is being moved and reacting on the blade, slides the beam to a new position established by the next opening in the rib. The locking pin automatically snaps into that next opening thereby setting the blade in a new position. Should the operator wish to set the blade in another position, he merely pulls the cord, cable, manipulates a lever, etc. in order to retract the pin from its new seat so that the same operation may take place. To adjust the blade in the opposite direction, the grader is moved backward or the blade is manually reset.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top view of a typical road grader and having a wing assembly thereon constructed in accordance with the invention.

Figure 2 is an elevational view of the beam that partially supports the blade of the wing assembly.

Figure 3 is a sectional view taken on the line 3—3 of Figure 2;

Figure 4 is an enlarged sectional view taken on the line 4—4 of Figure 1.

Figure 5 is a longitudinal sectional view through a part of the sleeve and beam assembly.

Figure 6 is a view partially in elevation and partially in section showing the sleeve within which the beam is mounted.

In the accompanying drawings there is a typical road grader 10. This is standard equipment. Wing assembly 12 is mounted on the road grader and on the right side thereof. The road grader could be equipped with another wing assembly on the left side or could be equipped with

2

a wing assembly only on the left side, these being variations that fall within the invention.

Wing assembly 12 is made of a blade 14 having the inner end thereof mounted on a vertical pivot 16. The 5 vertical pivot is attached to the road grader 10 between the front wheels 18 and the intermediate wheels 20 thereof by means of a mounting bracket 22. Mounting bracket 24 is attached to the rear surface of the blade 14 near the outer end of the blade. A vertical pivot 26 is 10 attached to mounting bracket 24 and to the front end of beam 28. As seen in Figure 2, vertical pivot 26 may be made of hinge butts with a vertical hinge pin passing therethrough. The same holds true for vertical pivot 16. Beam 28 is preferably hollow tubing or pipe and has an 15 elongated rib 32 extending longitudinally down its surface. This rib is rectangular in cross section and can be welded or otherwise fixed to the tubing or pipe part of the beam. It has a plurality of spaced openings 34 located in it and extending from one end of the rib to the 20 other end. These openings are equally spaced and are passed through passageway 36 that is formed in the top part of guide sleeve 38.

The guide sleeve is attached to mounting bracket 40, the latter welded or otherwise secured to the aft part of 25 the road grader 10 and protruding laterally therefrom. Vertical pivot 42, such as a pair of hinge butts and a vertical hinge pin, make the pivotal connection between guide sleeve 38 and mounting bracket 40. The sleeve has its major part cylindrical in form. However, there 30 is a small elongate casing 44 formed in the wall and constituting the side walls of passageway 36.

The casing 44 has a locking pin 48 slidably disposed therein and constrained in its movement by being located in passage 57 that extends transversely through both side 35 walls of the small casing 44. The outer end of the pin 48 is attached to a lever 50. The lower end of the lever is mounted on an ear 52, this being fixed to the side wall of guide sleeve 38. The upper part of the lever 50 has a pull rope or cable 56 secured to it. The intermediate 40 part of the lever 50 has a spring 58 or corresponding yielding device, mounted on it, as by being on a centering pin. The opposite end of spring 58 is disposed in a small recess in bracket 60, the latter fixed to casing 44 and having sides between which the lever is adapted to 45 rock. The bias of spring 58 is in a direction to keep pin 44 engaged in one of the openings 34. Therefore positive force is necessary to move the pin 48 in a direction to separate it from the opening 34, and after the positive force is relaxed, spring 58 pushes on the lever 50 in a 50 direction tending to return the pin 48 into one of the openings 34.

Cable 56 is reeved under an idler pulley 62 that is mounted on bracket 40. The cable is reeved over pulley 64 at the top of a standard 66 which rises from bracket 55 40. Pulley 64 is used merely for directing the cable 56 toward the seat of the grader 10. The cable can be attached to an eye on or near the seat or to a lever 68 to facilitate the operation of the pull cable or rope.

In use the pulling of the pull cable or rope will cause 60 the pin 48 to be released from the hole 34 that it is at that moment occupying. Thereafter the blade 14 will be moved rearwardly due to pressure applied thereon or friction generated by the blade scraping on a comparatively stationary object or objects. This will correspondingly move the beam 28 rearwardly in its guide sleeve 38 until the second position is established by pin 48 snapping into the next opening 34 or to any subsequent opening in accordance with the desires of the operator.

70 The foregoing is considered as illustrative only of the principles of the invention. Further, since numerous modifications and changes will readily occur to those

skilled in the art, it is not desired to limit the invention to the exact construction and operation shown and described, and accordingly, all suitable modifications and equivalents may be resorted to, falling within the scope of the invention as claimed.

What is claimed as new is as follows:

A side wing assembly for a road scraper comprising an elongated blade having an inner end, a hinge bracket on the inner end of said blade attachable to a road grader and having a vertical pivot on which said blade is swingable laterally, means for retaining said blade in laterally swung positions comprising a beam having one end pivoted to said blade for swinging of said blade laterally and for longitudinal adjustment thereof in response to lateral swinging of the blade, a guide sleeve for said beam through which said beam is longitudinally slidably adjustable, a hinge bracket on said sleeve attachable to a road scraper and on which said sleeve is swingable laterally to compensate for lateral swinging of the beam, and means for releasably locking the beam to the sleeve in different longitudinally adjusted positions of the beam comprising a longitudinal rib on said beam having longi-

tudinally spaced apertures therein, a locking pin slidable on said sleeve into and out of a selected aperture in the rib into and out of locking position and spring loaded for sliding into locking position, a lever pivoted on said sleeve and to said locking pin for operation to move said locking pin into unlocking position, and manual means for operating said lever from a driver's seat of a road grader, said manual means comprising a standard on the second named hinge bracket, upper and lower pulleys on said standard and second named hinge bracket respectively, and a cable attached to said lever and trained around said pulleys.
